(57) **CLAIM**

The ornamental design for a tire inflator, as shown and described.

DESCRIPTION

FIG. 1 is a front isometric view of the tire inflator embodying the new design showing visually tangential edges.

FIG. 2 is a front view thereof.

FIG. 3 is a rear view thereof.

FIG. 4 is a left view thereof.

FIG. 5 is a right view thereof.

FIG. 6 is a top view thereof; and,

FIG. 7 is a bottom view thereof.

Broken lines form no part of the design to be patented.
